UNITED STATES PATENT OFFICE

EDWARD D. BUFLMYER AND OLAF HELSTROM, OF WILLAPA, WASHINGTON

TOILET

Application filed April 27, 1931, Serial No. 533,284. Renewed February 20, 1932.

This invention relates to a toilet and especially to a device of this character which is particularly intended and designed for use on passenger carrying vehicles such as long distance buses but it is understood, of course, that a toilet in accordance with this invention may be used in any manner for which same may be found adapted and desirable.

An important object of the invention is to provide a toilet of the aforementioned character which will be very compact in construction and arrangement, thereby requiring a minimum of space in the vehicle in which same is installed.

Another very important object of the invention is to provide in a manner as herein-after set forth, a toilet of the character described embodying means for automatically flushing same after the use thereof and when 20 the bowl is swung to its raised or inoperative position.

Other objects of the invention are to provide a toilet of the character set forth which will be simple in construction, strong, durable, 25 efficient and reliable in operation, and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view partly in side elevation and partly in vertical section through a toilet constructed in accordance with the present invention.

Figure 2 is a view partly in side elevation and partly in vertical section showing the toilet in inoperative position.

Figure 3 is a horizontal sectional view taken substantially on the line 3—3 of Figure 2.

Figure 4 is a view in front elevation of the toilet showing the same in operative position, as in Figure 1.

Referring now to the drawings in detail, it will be seen that the reference numeral 1 designates a housing of suitable shape and size having an open side disposed in abutting en-

gagement with a wall 2 of the vehicle or other structure in which the toilet may be installed.

The wall 2 is provided with a hinged door 3 through the medium of which access may be had to the interior of the housing 1 for a purpose which will be more fully hereinafter set forth. Above the housing 1 the wall 2 is further provided with a recess or depression 4, the purpose of which will also be presently set forth.

A bowl 5 having a rim portion 6 thereon is mounted by a hinge 7 for swinging movement in a vertical plane on the housing 1 toward and away from the recessed portion 4 of the wall 2. The hinge construction which connects the bowl 5 to the housing 1 is such that the downward swinging movement of said bowl will be arrested when the bowl is disposed in a horizontal plane, as seen in Figure 1. When the bowl is swung upwardly, 70 the rim portion 6 thereof is adapted to enter the recess 4 of the wall 2, as seen in Figure 2 of the drawings.

An arcuate, telescopic sectional pipe 8 extends from the rear upper portion of the bowl 5 downwardly into the housing 1 through an opening provided therefor in the top of said housing and terminates in an elbow 9 which is rigidly mounted in the housing. The elbow 9 is provided with an externally flanged, 80 downwardly directed discharge branch which is detachably connected to the tapered neck 10 of a septic tank 11 which is removably disposed in the housing 1 in a manner to provide a leakproof joint through the medium of a suitable coupling clamp 12 which is illustrated to advantage in Figure 3 of the drawings. It will be seen that the clamp 12 comprises a pair of complementary, pivotally connected jaws having suitable means on their free ends for yieldingly clamping said free ends together. The jaws of the clamps 12 are provided with a substantially V-shaped channelled groove for the reception of the tapered neck 10 and the tapered flange on 95 the lower end of the elbow 9, as best seen in Figure 1 of the drawings.

The reference numeral 13 designates a back rest which is mounted for vertical swinging movement in a direction at right angles to

the movement of the bowl 5 on a suitable supporting bracket 14 on the wall 2, the back rest 13 having an arm 15 extending from its periphery, an intermediate portion of said 5 arm being pivotally connected to the supporting bracket 14. A suitable operator 16 is mounted on the housing 1 coaxially with the bowl 5 and is operatively connected to said bowl in a manner to yieldingly urge same 10 upwardly to raised or inoperative position as at 17. A cable 18 has one end connected to the operator 16 for actuation thereby and is trained over suitable pulleys 19 and has its other end connected to the free end portion of 15 the arm 15 of the back rest 13, as illustrated to advantage in Figure 4 of the drawings. Thus, when the operator 16 swings the bowl 5 to its raised or inoperative position, the back rest 13 will, through the medium of the 20 cable 18, be swung upwardly to its inoperative position as indicated in broken lines in Figure 4 of the drawings to permit the rim portion 6 of the bowl to enter the recess or depression 4 in the wall 2.

25 The reference numeral 20 designates a water storage tank or reservoir which is mounted on the wall 2 or on any other suitable structure above the back rest 13. A measuring container 21 is connected to the lower end 30 of the reservoir 20 by a valved coupling 22. The reference numeral 23 designates a flush pipe which is connected to the measuring container or tank 21 by a valve 24. The flush pipe 23 terminates in a substantially U-shaped 35 lower end portion which is formed to accommodate the free end portion of the bowl 5, when said bowl is in its raised or inoperative position, the free end portion of the flush pipe projecting into the bowl in the manner illustrated to advantage in Figure 2 of the drawings. The valves 22 and 24 are provided with common actuating means for simultaneous 40 operation in the form of a rod 25 having its lower end pivotally connected to one end of a 45 pivotally mounted bell crank lever 26. A suitable spring 27 normally maintains the valve 24 in its closed position and the upper valve 22 in its open position.

The reference numeral 28 designates an air 50 valve which is connected by a pipe 29 with the upper end of the measuring container or tank 21. The air valve 28 is connected by a pipe 30 with the air brake system of the vehicle or with any other suitable source of 55 air pressure supply. The valve head of the air valve 28 is mounted on a reciprocating stem 31 having a coil spring operatively connected thereto for yieldingly urging the valve toward its closed position. On its lower end 60 the valve stem 31 is provided with suitable spring controlled pivoted means disposed in the path of the upper end of the rod 25 for engagement and actuation thereby in a manner to open the valve 28 when the rod 25 is moved upwardly but to permit downward movement

of the rod 25 independently of the valve 28.

In use, the bowl 5 is swung downwardly from the position illustrated in Figure 2 to the position illustrated in Figure 1 of the drawings, a suitable handle 32 being provided on the bowl for this purpose. When the bowl is swung downwardly the operator 16 is actuated in a manner to draw the cable 18 toward the back rest 13 and thus permit such back rest to swing downwardly to its operative position. It may be well to here state that the telescopic, arcuate pipe 8 is disposed concentrically with the axis about which the bowl 5 swings. After being used, the bowl 5 is again swung upwardly by the operator 16, the sections of the pipe 8 telescoping within each other and the cable 18 again swinging the back rest 13 outwardly and upwardly to its inoperative position to permit the rim portion 6 of the bowl to enter the recess or depression 4 in the wall 2. When the bowl enters the recess or depression 4, the upper end portion thereof engages the free end portion of the bell crank lever 26 in a manner to swing the rod 25 upwardly and open the valve 24 and close the valve 22. This same movement of the rod 25 opens air valve 28 to admit air under pressure into the upper end of the measuring tank or compartment 21 and the water therein will be discharged through the pipe 23 with considerable force into the upper portion of the bowl 5 in a manner to thoroughly flush said bowl, the flushing water passing downwardly through the telescopic pipe 8 into the septic tank 11. It will be seen that the pressure of the air is added to the force of gravity on the flushing water which passes downwardly through the pipe 23. It may be well to here state that when the bowl 5 is swung downwardly for use, the spring 27 closes the valve 24 and opens the valve 22 in a manner to permit the measuring tank 21 to be filled from the reservoir 20 while the bowl is in use. Obviously, when the bowl is not in use and has been flushed the measuring tank 21 is empty and the valve 22 is closed.

The tank 11 may be expeditiously removed and replaced through the hinged door 3 by removing the coupling clamp 12.

It is believed that the many advantages of a toilet constructed in accordance with this invention will be readily understood, and although the preferred embodiment of the invention is as illustrated and described, it is to be understood that changes in the details of construction, and the arrangement of parts may be resorted to without departing from the spirit of the invention as claimed.

What is claimed is:

1. A toilet comprising a supporting structure, a bowl mounted for swinging movement in a vertical plane on the supporting structure, a back rest mounted shiftably on a support adjacent the rear of the bowl, and means

operatively connecting the back rest to the bowl for shifting said back rest to inoperative position when the bowl is swung upwardly.

5 2. A toilet comprising a supporting structure, a bowl mounted for swinging movement in a vertical plane on the supporting structure, a back rest mounted for swinging movement in a vertical plane adjacent the rear of 19 the bowl, and a cable operatively connecting the back rest to the bowl for actuation thereby in a manner to swing said back rest to inoperative position when the bowl is swung upwardly.

15 3. A toilet comprising a supporting structure, a bowl mounted for swinging movement in a vertical plane on the supporting structure, a back rest mounted for swinging movement in a vertical plane in a direction at right 20 angles, to the direction of movement of the bowl and adapted for disposition adjacent the bowl when in its operative position, and means operatively connecting the back rest to the bowl for actuation thereby in a manner 25 to swing said back rest from its operative to its inoperative position when the bowl is swung upwardly.

4. A toilet comprising a supporting structure, a bowl mounted for swinging movement on the supporting structure, a back rest mounted for swinging movement adjacent the bowl, and common means operatively connected to the bowl and to the back rest for swinging said bowl and back rest to inoperative position.

5. A toilet comprising a supporting structure, a bowl mounted for swinging movement in a vertical plane on the supporting structure, a back rest mounted for swinging movement in a vertical plane substantially at right angles to the bowl and disposed adjacent the bowl when in its operative position, and common means operatively connected to the bowl and to the back rest for simultaneously freeing said bowl and the back rest upwardly to their inoperative positions.

6. A toilet comprising a supporting structure, a bowl mounted for swinging movement in a vertical plane on the supporting structure, said bowl being disposed substantially in a horizontal plane when in its operative position and in a vertical plane when in its inoperative position, a liquid reservoir mounted above the horizontal plane of the bowl, valve controlled discharge means connected to the reservoir, means for operating the valve controlled discharge means disposed in the path of the bowl for engagement and actuation thereby when said bowl is swung upwardly to 80 its inoperative position, a shiftable back rest mounted adjacent the bowl and disposed between said bowl and the last named means when in its operative position, and means operatively connecting the back rest to the 85 bowl for actuation thereby when the bowl

is swung upwardly in a manner to swing the back rest to its inoperative position out of the path of the bowl for the passage of said bowl into engagement with the second named means.

7. A toilet comprising a supporting structure, a bowl mounted for swinging movement in a vertical plane on the supporting structure and disposed in a substantially horizontal plane when in its operative position 75 and in a substantially vertical plane when in its inoperative position, a liquid reservoir disposed above the bowl, a measuring tank disposed below the liquid reservoir, a valve connecting the measuring tank to the reservoir in a manner to receive liquid therefrom when the valve is open, a flush pipe having its discharge end disposed adjacent the bowl when said bowl is in its inoperative position, a valve connecting the other end of the flush 80 pipe with the lower end of the measuring tank, a rod connecting the valves together in a manner to open one of said valves when the other of said valves is closed, means operatively connected to the rod and disposed in 85 the path of the bowl for engagement and actuation thereby when said bowl is swung to its inoperative position in a manner to open the second named valve and to close the first named valve for discharging the contents of 90 the measuring tank in the bowl, means connecting the measuring tank to the source of air supply for receiving air under pressure therefrom, a valve interposed in the last last named means for controlling the flow 95 of air through the measuring tank, and means on the last named valve disposed in the path of the rod for engagement and actuation thereby in a manner to open said last named valve when the rod is moved in one direction.

In testimony whereof we affix our signatures.

EDWARD D. BUFMYER.
